(57) **CLAIM**

We claim the ornamental design for a boot clip, as shown and described.

DESCRIPTION

FIG. 1 is a front perspective view of a boot clip of the invention showing our new design, as attached to the top of a boot.

FIG. 2 is a front view of the boot clip.

FIG. 3 is a rear view of the boot clip.

FIG. 4 is a right side view of the boot clip.

FIG. 5 is left side view of the boot clip.

FIG. 6 is a top view of the boot clip; and,

FIG. 7 is a bottom view of the boot clip.

The broken line showing of the boot in FIG. 1 is to illustrate the design as it may appear when being worn on a boot, and forms no part of the claim. The broken line showing of the circular configuration of the boot clip of FIG. 1 through FIG. 7 is to illustrate a decorative feature which may be added to the boot clip, and forms no part of the claim. The broken line showing of the elongated hanging configuration of the boot clip of FIG. 1 through FIG. 7 is to illustrate a decorative feature which may be attached to the boot clip, and forms no part of the claim.
